Primary Examiner — Marissa J. Cash*Assistant Examiner* — Nicholas J Buffa(74) *Attorney, Agent, or Firm* — Leason Ellis LLP(57) **CLAIM**

The ornamental design for a tray as shown and described.

DESCRIPTION

FIG. 1 is a top perspective view of a tray according to my new design;

FIG. 2 is a bottom perspective view thereof;

FIG. 3 is a front elevation view thereof, the rear being a mirror image and therefore not illustrated in the drawing disclosure;

FIG. 4 is a left-side elevation view thereof the right-side being a mirror image and therefore not illustrated in the drawing disclosure;

FIG. 5 is a bottom plan view thereof; and,

FIG. 6 is a top plan view thereof.

The broken lines depict portions of the tray in which the design is embodied that form no part of the claimed design.

1 Claim, 6 Drawing Sheets(56)
